CLAIM

We claim the ornamental design for a display screen or portion thereof with a graphical user interface, substantially as shown and described.

DESCRIPTION

FIG. 1 is a front view of a display screen or portion thereof with graphical user interface showing our new design; and, FIG. 2 is a second embodiment thereof.

The two outermost broken lines from the graphical user interface illustrate the display screen. The remaining broken lines illustrate portions of the graphical user interface that form no part of the claimed design. None of the broken lines form part of the claimed design.
